(57) **CLAIM**

The ornamental design for a tactical scope, as shown and described.

DESCRIPTION

FIG. 1 is a perspective view of a tactical scope showing my new design.

FIG. 2 is a front view thereof.

FIG. 3 is a rear view thereof.

FIG. 4 is a right view thereof.

FIG. 5 is a left view thereof.

FIG. 6 is a top view thereof.

FIG. 7 is a bottom view thereof; and,

FIG. 8 is a perspective view of the tactical scope, illustrating tactical scope being coupled at a gun.

The broken line portion of the figure drawings is included to show unclaimed subject matter only and forms no part of the claimed design.
